UNITED STATES PATENT OFFICE.

RUDOLF WILD, OF LOS ANGELES, CALIFORNIA.

KNIFE-BLADE.

1,172,089.

Specification of Letters Patent. Patented Feb. 15, 1916.

Application filed April 12, 1911. Serial No. 620,633.

To all whom it may concern:

Be it known that I, RUDOLF WILD, a subject of the Emperor of Germany, residing at Los Angeles, in the county of Los Angeles and State of California, have invented certain new and useful Improvements in Knife-Blades; and I do hereby declare the following to be a full, clear, and exact description of the invention, such as will enable others skilled in the art to which it appertains to make and use the same.

This invention relates to certain new and useful improvements in knife blades, and in particular to one adapted to serve a variety of purposes.

The peculiar construction of the blade is such that it may be used with great efficiency for any of the following purposes: a paper creaser, envelop opener, paper cutter, ink eraser, graphite file and pencil sharpener.

With the above and other objects in view, the novelty of the invention resides in the peculiar combination and formation of the blade to be hereinafter more fully described, claimed and illustrated in the accompanying drawing, in which—

Figure 1 is a side elevation of the blade rigidly fixed in a straight handle; Fig. 2 is a side elevation of the blade pivoted within a frame; Fig. 3 is a side elevation of the blade as adapted to fit within a jack knife; Fig. 4 shows the blade used as an envelop opener; Fig. 5 shows the blade used as a graphite pointer; Fig. 6 shows the blade used as an ink eraser; Fig. 7 shows the blade used as a pencil sharpener, and Fig. 8 is an elevation of the edge of the blade.

Referring to the drawing by characters of reference, the numeral 1 represents in general the blade, on one end of which is formed the shank 2, this being shaped so as to be readily inserted in a fixed handle, as in Fig. 1, and to be pivoted within a frame, as in Fig. 2, or adapted to be pivoted within the handle of a jack knife, as in Fig. 3.

The blade of the knife, exclusive of the shank, is divided into approximately two sections, the section nearest the shank having file teeth 3 cut on both sides. The teeth are inclined to the edges of the blade at an angle of approximately 60°, and serve the purpose of sharpening a pencil lead to a point of any desired thickness.

The blade 1 has formed therein on oppo-

site sides thereof, and at points in advance of the file, a pair of diagonally extending recesses 5 which extend for approximately the entire width of the blade and have their lower ends extended in the direction of the forward end of the blade, said recesses having their rear walls arranged in converging relation toward the upper edge of the knife blade and terminally meeting at a point below the upper edge of the blade so as to provide a cutting edge, the mentioned cutting edge being ground into concave configuration as shown in the drawing. This cutting edge 5 is particularly adapted for sharpening wooden pencils, its concave edge forming an admirable cutting edge, and the angular manner in which this portion is ground out assisting materially in guiding the knife on the pencil.

The outer portion of the blade is ground from its approximate longitudinal center line down to a straight cutting edge 6, the rear part of this ground-out portion being recessed backward, as at 7, thus leaving a somewhat triangular shaped piece 8 of the same thickness as the original blade.

The outer end of the blade is ground away to a rounded point at 9, and its upper or back portion ground out to a cutting edge 10, which extends back about half the length of the edge 6.

The back edge of the blade is rounded off at 11, as shown in Fig. 8 to form a smooth surface for creasing folded paper.

The straight cutting edge 6 is particularly adapted for opening envelops or cutting creased paper, as in books, magazines, etc., because of the recessed portion at 7, which serves to spread the sides of the paper apart and give the edge 6 a smooth cutting action instead of the ripping or tearing action of the ordinary type of paper cutter.

The portion 8 adjacent the cutting edge 6 forms a stop shoulder having an inclined upper face 8a. The stop shoulder limits the thrusting movement of the blade and further acts as a guide in the operation of opening an envelop and cutting creased paper, as in books, magazines, etc.

The rounded end 9 serves as an ink eraser or for cutting out curved lines on paper, the edge 10 being used for cutting straight lines. The upper end of the cutting edge 10 is beveled sharply downward from the full thickness of the blade, as at 12, thus

forming an admirable pencil lead pointer, the lead sliding against this beveled portion, which thus serves as a guide.

An additional feature is provided at the 5 rear end of the shank when this is pivoted within a frame, as illustrated in Fig. 2. The end of the shank is rounded out at 13, and its center portion ground out to a somewhat chisel-like cutting edge 14, extending only 10 part of the way across the end of the rounded portion. This is particularly adapted for sharpening the soft lead of heavy marking pencils, and because of its chisel-like action is less apt to break the 15 lead than is the case when other means are employed.

Having thus fully described this invention, what I claim as new and desire to secure by Letters Patent is:

20 A knife blade having a longitudinally ex-

tending cutting edge, and having a concaved recess on each side of the blade, the said recesses extending diagonally of the blade, and approximately for the entire width of the blade, having their lower ends extending in the direction of the forward end of the blade, the said recesses having their rear walls arranged in converging relation toward the cutting edge of the knife, and terminating at a point below the cutting edge 25 and providing a second cutting edge, the said last mentioned cutting edge being concaved, as for the purposes specified. 30

In testimony whereof I affix my signature in presence of two witnesses.

RUDOLF WILD.
